No. 888,925.

PATENTED MAY 26, 1908.

M. W. POOL.
TYPE WRITING MACHINE.
APPLICATION FILED MAR. 18, 1905.

HIS ATTORNEY

UNITED STATES PATENT OFFICE.

MORRIS W. POOL, OF NEW YORK, N. Y., ASSIGNOR TO THE MONARCH TYPEWRITER COMPANY,
OF SYRACUSE, NEW YORK, A CORPORATION OF NEW YORK.

TYPE-WRITING MACHINE.

No. 888,925.

Specification of Letters Patent.

Patented May 26, 1908.

Application filed March 13, 1905. Serial No. 249,889.

To all whom it may concern:

Be it known that I, MORRIS W. POOL, citizen of the United States, and resident of the borough of Brooklyn, city of New York, in the county of Kings and State of New York, have invented certain new and useful Improvements in Type-Writing Machines, of which the following is a specification.

My invention relates more particularly to 10 the type bar actuating mechanism of type-writing machines. The main object of the invention is to improve the connection between the type bar and its actuating mechanism. 15 To the above and other ends the invention consists in the features of construction and combinations of devices hereinafter fully set forth and particularly pointed out in the claims.

20 In the accompanying drawings, Figure 1 is a skeleton view in side elevation of a type bar and its actuating mechanism; Fig. 2 is an enlarged fragmentary top plan view; Fig. 3 is a view taken on a plane indicated by the 25 line x of Fig. 2; Fig. 4 is a view similar to Fig. 3, but showing the parts in positions different from those in which they appear in said figure, and Fig. 5 is an enlarged fragmentary side elevation, partly in section, of a modification.

30 In the drawings 1 indicates the frame work of the machine, 2 a platen, 3 one of a series of key levers fulcrumed on a fulcrum plate 4 and having a restoring spring 5. 35 Pivoted to each key lever at 6 is a sub-lever 7, the lower portion whereof co-operates with a fixed abutment 8. The upper end of each sub-lever is connected by a link 9 with a type bar 10 in a manner hereinafter fully described. 40 Each type bar may be pivoted in a hanger 11 secured to a hanger support 12 and is adapted to coact with the platen 2 when the associate key lever 3 is adequately depressed.

45 As best appears in Figs. 3 and 4, the rear upper portion of the main central part of each type bar 10 is cut away at 13 and to each side of this rear portion a side member or cheek piece 14 is secured in any suitable 50 manner, preferably by rivets 15. The tail of the type bar, comprising the two cheek pieces and the central portion, is perforated to receive a pivot pin 16 which passes through the three-ply of metal at right angles to the 55 outer faces of the cheek pieces. The pivot

pin has its bearings in the associate hanger 11. The cheek pieces 14 are shaped to conform to the rear end of the central part of the type bar, the construction providing a long seat for the pivot of the bar and enabling 60 said pivot to be held securely in position. Above the cut-away 13 of the central part of the type bar the inner face of each cheek piece is formed with a recess or depression 17, the shape of which is most clearly indicated 65 in Figs. 2 and 4. It will be noted that the center part of the type bar is also further cut away at 18, forming, with the depressions 17 in the cheek pieces, a seat or pocket adapted to receive the rounded, 70 spherical or ball-shaped forward end 19 of the connecting link 9. When the spherical end 19 of the link is in position in this bearing pocket, the mouth of the latter is closed by a member, which, as shown in Figs. 2 75 to 4 is in the form of a spring piece 20 which is secured to the type bar in any suitable manner as by a rivet 21. The forward end of the retaining member 20 is bent inwardly at 22 and shaped to conform with 80 the surface of the spherical portion 19 with which the part 22 normally contacts. The link 9 may be connected with its associate sub-lever 7 in any suitable manner. As herein shown the rear end of the link is flattened and perforated at 23 to receive a rivet 24 which also passes through the sub-lever and connects the latter with the link 9. 85

In practice the key levers and their associate sub-levers and connecting links are assembled in the machine and the type bar hangers with the type bars pivoted therein are radially adjusted and secured on the support 12. Each type bar in turn may then be raised slightly from normal position, as indicated in Fig. 4. The spring guard or retainer 20 may then be pulled away from the bar, as indicated in said figure, and the associate link 9 may be swung down between the inner faces of the cheek pieces 14, so that the 90 spherical end 19 will enter the mouth of the pocket-like bearing formed by the depression 17 in the cheek pieces and the depressed part 18 of the central part of the type bar. The spring guard or retainer 20 may then be 95 released so that it may move back until the part 22 contacts with the spherical end 19 of the link 9. By the employment of this construction a saving of time is effected in assembling the parts of the type bar actuating 100 105 110

mechanism, as it is only necessary to mount and adjust the parts in the machine in the manner described and then to pull the spring guard or retainer 20 far enough away from the type bar to permit the rounded end of the connecting link 9 to be slipped into its bearing in the type bar. Any type bar and hanger may be removed from the machine without disturbing its associate actuating mechanism by manipulating the retainer 20 and the link 9 in the manner illustrated in Fig. 4.

I have shown my invention embodied in a construction resembling generally that of the Monarch typewriter, the parts of the machine not necessary to a clear understanding of the invention being omitted. It is to be understood, however, that the invention is adapted to other forms of writing machines; and it is further to be understood that various changes in the construction and arrangement of the parts may be effected within the scope of the invention. One example of such changes is illustrated in Fig. 5 of the drawings, wherein is shown a type bar 25, the rear portion of which is thickened as indicated at 26. The face 27 of the thickened portion which normally is vertically disposed is formed with a pocket-like depression 28 which is threaded to receive a screw 29. A slot 30 formed in the rear part of the bar corresponds to the opening between the inner faces of the cheek pieces in the first described construction and said slot permits play of the link 9 therein. When the type bar is of the construction just described it and its associate mechanism may be assembled in the machine as hitherto explained and when the bar is swung to the printing point the spherical end 19 of the link is dropped into the pocket-like bearing 28 and then the retaining screw 29 is screwed into place, the bottom of said screw being cupped out to conform to the surface of the spherical end of the link and contacting with said end when in place. In Fig. 5 the type bar is represented as in printing position, but it is to be understood that the ball and socket joint may be connected and disconnected when the bar is in a position corresponding to that shown in Fig. 4. The construction shown in Fig. 5, it will be observed, enables a one piece type bar to be employed and requires only such manipulation as described to connect or disconnect the type bar and its associate link.

The ball and socket connection between the type bar and its actuating mechanism shown in my present invention permits the parts to move in different planes without causing any bind. The slot 30 in the modification and the corresponding space between the cheek pieces in the first described construction form a trough wherein the connecting link may play freely up and down or from side to side or intermediately, thereby

permitting a free movement of the parts of the type actuating mechanism. The median plane of the type bar will always be coincident with a plane passing through the center of the spherical end 19 of the connecting link so that stresses incident to the bar during its movements are equally distributed between its two pivots, thereby conducing to uniform wear in the type bar bearings. During the operation of the machine actuating impulses are communicated to the type bar from the spherical end 19 through the bottom and sides of its pocket-like recess or elongated open mouth socket, and the part closing the mouth of the recess receives little, if any, stress or thrust from the link 9. The constructions described are such that each type bar may be readily disconnected from or connected with its actuating mechanism from the front of the machine without disturbing any of the other type bars.

Various other changes in details of construction and arrangements of parts may be effected within the scope of the invention.

What I claim as new and desire to secure by Letters Patent, is:—

1. In a type bar action, the combination of a type bar having an elongated open mouth socket; an actuating link provided with a ball which occupies the bottom portion of the socket, the mouth portion of said socket extending beyond the ball; and a closure occupying the extended mouth portion of said socket.

2. In a type bar action, the combination of a type bar having an open-mouthed socket, said socket having closed sides; an actuating link having a ball seated in said socket, and a retaining device normally located in the mouth of the socket and movable outward through the mouth of said socket to permit detachment of said ball from said socket.

3. In a typewriting machine, the combination of a type bar having a recess therein; a connecting link having a rounded end fitting into said recess; a member normally closing the mouth of said recess and adapted to be moved so as to permit the link to be disconnected from the type bar; and means for actuating said link, the construction being such that relative movement only between the link and type bar may effect disconnection of said link from said type bar.

4. In a typewriting machine, the combination of a type bar having a recess therein; a connecting link having a rounded end fitting into the recess in the type bar; a member normally covering the mouth of the recess and contacting with the end of the link, said member being adapted to be moved to permit said link to be disconnected from said type bar; and means for actuating said link, the construction being such that relative movement only between the link and type

bar may effect disconnection of said link from said type bar.

5. In a typewriting machine, the combination of a type bar having a recess and a trough-like portion; a connecting link adapted to play in said trough-like portion and having a rounded end fitting into the recess in the type bar; a spring retainer adapted to confine the rounded end of the link within the recess in the type bar, said retainer being adapted to yield so as to permit the link to be separated from the type bar; and means for actuating said link.

6. In a typewriting machine, the combination of a type bar having an open mouthed bearing therein; a link provided with a rounded end normally seated in said bearing; a spring retainer normally contacting with the end of the link and closing the mouth of the bearing, said retainer being adapted to be moved to permit the link to be withdrawn from its bearing; and means for actuating said link.

7. In a typewriting machine, the combination of a type bar having an open mouthed socket; a ball fitting in said socket; a link connected with said ball at one end; actuating means connected with the other end of said link; and means normally confining the ball within said socket; said means being adapted to be moved to permit the ball to be withdrawn from its socket, the construction being such that relative movement only between the link and type bar may effect disconnection of said link from said type bar.

8. In a typewriting machine, the combination of a type bar having an open mouthed socket; a ball fitting in said socket; a link connected with said ball at one end; actuating means connected with the other end of said link; and a spring retainer normally contacting with the ball and closing the mouth of the socket, said retainer being adapted to yield to permit the ball to be withdrawn from the socket.

9. In a typewriting machine, the combination of a type bar having an open mouthed socket; a ball fitting in said socket; a link connected with said ball at one end; actuating means connected with the other end of said link; and means normally closing the mouth of said socket, the parts being so arranged that the median plane of the type bar always passes through the center of the ball when the parts are operatively connected, the construction being such that relative movement only between the link and type bar may effect disconnection of said link from said type bar.

10. In a typewriting machine, the combination of a type bar having an open mouthed socket; a ball fitting in said socket; a link connected with said ball at one end; actuating means connected with the other end of said link; and a spring retainer normally contacting with the ball and closing the mouth of the socket, said retainer being adapted to yield to permit the ball to be withdrawn from the socket, the arrangement being such that the median plane of the type bar is always coincident with a plane passing through the center of the ball when the parts are operatively connected.

11. In a type bar action, the combination of a three-ply type bar, the center ply being cut away to form a trough; an actuating link adapted to play in said trough and provided with a rounded end bearing in the side plies of said type bar; and a device secured to the type bar and co-operating with the rounded end of said link to prevent its displacement from its bearing.

Signed at the borough of Manhattan, city of New York, in the county of New York and State of New York, this 11th day of March, A. D. 1905.
